ELLÉS E. HARTMAN, OF NEW YORK, N. Y.

COLLAPSIBLE SUITCASE.

1,319,072.

Specification of Letters Patent. Patented Oct. 21, 1919.

Application filed January 28, 1919. Serial No. 273,629.

To all whom it may concern:

Be it known that I, ELLÉS E. HARTMAN, a subject of the King of Hungary, residing at New York city, county and State of New York, have invented certain new and useful Improvements in Collapsible Suitcases, of which the following is a full, clear, and exact description.

This invention relates to improvements in foldable structures, such as suit cases, trunks, etc., the object being to provide a suit-case or trunk that can be knocked down or folded, when not in use, into flat formation, in which formation it will take up but little space. My improved foldable structure, whether embodied in the form of a suit-case or trunk, will be found very useful for theatrical performers, especially those who do considerable traveling, such as vaudeville artists, who frequently encounter limited quarters to store their trunks, etc.

I will now describe my improved foldable structure in detail, reference being had to the drawing, wherein:

Figure 1 is a perspective view of my improved device set up to form a table;

Fig. 2 is an enlarged cross-sectional view thereof;

Fig. 3 is an enlarged fragmentary sectional view illustrating the manner of connecting the members to form a suitcase or trunk;

Fig. 4 is a top plan view of one corner of the body of the device;

Fig. 5 is an enlarged fragmentary vertical sectional view, the section being taken on a line 5—5 in Fig. 4;

Fig. 6 is an enlarged sectional plan view, the section being taken on a line 6—6 in Fig. 5.

Fig. 7 is an enlarged longitudinal sectional view of the device folded;

Fig. 8 is a bottom plan view thereof;

Fig. 9 is an enlarged vertical sectional view illustrating the manner of detachably hinging the cover to the body of the structure; and

Figs. 10 and 11 are detail perspective views of the hinge-members.

In describing my improved structure, I will refer to it as a suit-case, but it will be understood that the same may be embodied in the form of a trunk or the like; in any event, the structure is made up of a bottom-member 12 having side members 13 and 14 and end-members 15 and 16; one end mem-

ber being illustrated in Fig. 2, while in Fig. 8, both end members are illustrated. The side-members 13 and 14 and end members 15 and 16 are hinged at 17, 17, and 18, 18, respectively, to the corresponding edges of the bottom-member 12, the side-members 13 and 14 being arranged to fold inwardly, or toward each other, and lie upon the upper surface of the bottom 12. The end-members 15 and 16 are arranged to fold under and lie against the under surface of the bottom 12, as illustrated in Fig. 7.

To lock the side and end-members together when positioned to form a suit-case, I provide the ends thereof with intermeshing tongues 19 and 20 extending from plates 21 and 22, respectively, (see Fig. 5), the plates 22 being secured to the end-members of the structure and the plates 21 to the side members. In other words, each end-member 15 and 16 will have secured thereto, at each end, a plate 22 carrying tongues 20 to intermesh with similar tongues 19 carried by plates 21 secured at the ends of the side-members 13 and 14. The tongues 19 and 20 are each provided with openings 23 therethrough that will align one with the other when the members 13, 14, 15 and 16 are set up to form the suit-case. To lock the members after they have been set up, I employ locking-bars 24 and 25 connected by a cross-member 26, in order that the two bars can be simultaneously operated. The bars 24 and 25 pass through the aligned openings in the tongues 19 and 20. To prevent the complete withdrawal of the locking-bars, I flatten one side thereof as at 27 (Figs. 5 and 6), and insert a pin 28 in the uppermost tongue 20 (see Fig. 5). Adjacent the lower end of the bars 24 and 25, a shoulder 29 is provided which will prevent the locking-bars from being completely withdrawn, thereby obviating the chance of losing same. The locking-bars, when raised or pulled upwardly until pins 28 strike shoulders 29, will permit the side and end members of the suit-case to be released one from the other in order that they can be folded. After the side and end members have been separated or moved out of engagement, one with the other, the locking-bars can be pushed downwardly through the tongues 20; hence will not project from the end-members, when said members are folded.

Another element of the combination con-

sists of a cover or top 29 which is hinged to one of the side-members (in this instance side-member 13), when the case is set up for use, but which is disconnected from the said side-member when the case is folded. In other words, I employ a releasable hinge to connect the top and side-member of the case. Referring to Fig. 9, the hinge consists of a resilient socket-member 30, which is carried by the side-member of the case, and a trunnion-member 31, which is rounded and carried by the top or cover 29. As can be seen, the socket-member 30 is located on the inside of the side-member of the case opposite to an opening 32 therein through which the support 33 for the trunnion-member 31 passes. The opening 32 will be wide enough to permit the cover of the case to be opened sufficiently to suit all purposes. When the case is to be folded the cover will be disengaged therefrom by pulling the trunnions 31 out of the sockets 32. When the case is to set up the trunnions 31 will be forced into said sockets.

In order that the case can be used as a table, I provide the bottom thereof with foldable legs 34 and 35 which do not interfere with the use of the device for suit-case purposes, but adapts the same for use as a table which will be found very convenient at times. The case will be provided with the usual lock 36 and hasp-fasteners 37.

To fold the case the locking bars or rods will be withdrawn, the sides folded inward to lie upon the bottom member, and the ends folded under to rest against the underside of the bottom, the top of course having been separated from the side-member 13. After the sides and ends have been folded as above described, the top or cover will be applied to cover the folded over ends of the case as indicated in Fig. 7. In connection with the lock and hasps, I employ straps 38 and 39 to secure the top or cover to the body of the case when set up for use, said straps being employed to secure the members of the case together when they are folded. In other

words, after the case has been folded it will be turned over and the cover 29 applied to what was the under portion of the case, thereby covering the folded ends. The straps 38 and 39 will be caused to engage the buckles carried by the side-members 13 and 14 after the cover has been applied as described, thereby maintaining the folded structure together.

Having described my invention, what I claim is:

1. In a suit case, a bottom-member, side and end-members hinged thereto, locking elements carried by the side-members, co-operating locking members carried by the end-members, locking-bars movably supported by the end-members to engage the locking elements carried by the side and end-members, a shoulder carried by each locking-bar adjacent one end thereof, and pins carried by the end-members to engage said shoulders to prevent the withdrawal thereof from said end members. 70

2. In a suit case, a bottom-member, side and end-members hinged thereto, tongues carried by the side members at the ends thereof, said tongues being spaced one from the other and provided with openings there-through, similar tongues carried by the end-member arranged to fit in the spaces between the tongues on the side members, said last named tongues having openings to align with the openings in the first named tongues, locking-bars arranged to pass through the openings of all of said tongues, said locking-bars being provided with a flattened portion to provide shoulders, and pins carried by the uppermost tongues of each end-member to prevent the complete withdrawal of the locking-bars. 80

Signed at New York city, N. Y., this 20 day of January, 1919.

ELLÉS E. HARTMAN.
